VALVE FOR TANK CARS AND THE LIKE.

Application filed December 12, 1925. Serial No. 74,997.

The invention relates to an improvement in valves for tank cars and the like.

The usual type of outlet valve for tank cars and similar structures comprises a flattened or disk-like plug having on its underside a beveled bearing surface adapted to seat against a beveled, annular seat in a casting secured to the bottom of the tank, which casting performs the function of the usual valve casing and constitutes the outlet opening of the tank. The plug is manipulated to open and close the outlet opening by means of a vertically arranged stem or rod extending upwardly through the tank and provided at its upper end with a cam and handle.

By reason of the fact that the oil, gasoline and other liquids carried by tank cars usually contain particles of sand and other grit, the bearing surfaces of the plug and the valve seat in the casing become scored and are thereby caused to leak. This necessitates a regrinding or lapping of the bearing surfaces. To accomplish this regrinding of tank car valves it has heretofore been necessary to drain the contents from the tank and, if it was used for the transportation of oil or gasoline, thoroughly cleanse the tank with live steam and then ventilate it before the workmen could enter the tank for the purpose of repairing the valve. These operations have usually been effected in the repair yard. The switching of the car to the repair yard, the cleansing and ventilating of the tank, and the regrinding of the valve usually require from 24 to 48 hours. Moreover, the expense involved in switching, steaming and regrinding within the tank, and loss of time in the use of the car is considerable.

The object of the present invention is to produce an improved outlet valve for tank cars and the like provided with means whereby the seating surfaces of the valve may be reground or lapped while the tank is in commission and is partly or completely full of oil, gasoline or other liquid, thereby obviating the necessity and expense of draining the liquid from the tank, cleaning it out either by steam or otherwise, and switching the car to the repair yard for the valve grinding operation. To the accomplishment of this object the invention consists in the improved valve for tank cars and the like

hereinafter fully described and particularly pointed out in the appended claims.

In the accompanying drawings illustrating the preferred form of the invention, Fig. 1 is a view showing the improved valve in vertical section and the means for operating the valve in side elevation; Fig. 2 is a longitudinal section on an enlarged scale of the upper part of the valve operating means shown in Fig. 1; Fig. 3 is a view similar to Fig. 1, but taken at right angles thereto; and Fig. 4 is a section taken along the line 4—4 of Fig. 1.

The improved valve for tank cars and the like as illustrated in the drawings comprises a movable member or valve proper 5 which is a flattened plug provided on its underside with the beveled bearing or seating surface 6 adapted to seat against the beveled annular seat 7 formed in the upper end of an outlet pipe 8 provided with the circumferential flange 9 arranged to be secured by the rivets 70 11 to the underside of the rim of a hole 12 cut in the bottom 10 of the tank. The outlet pipe 8 drains the contents of the tank through the hole 12. The valve structure 75 constituted by the plug 5 and the seat in the upper part of the pipe 8 is opened and closed by unseating and seating the plug 5 by a vertical movement from and toward the seat 7. For this purpose the valve stem or rod 14 connected at its lower end with the plug 5 and extending upwardly through the tank into the dome 15 at the top thereof is provided with a cam member 16 having an operating handle 17. The cam surface 18 of the member 16 bears against the upper surface of the inner end of a bracket 19 secured at its outer end to the dome 15. The inner end of the bracket 19 is provided with a hole 80 through which the stem 14 passes loosely. The cam member 16 is bored to pass freely 85 over the valve stem 14 and is free to turn thereon at all times. By turning the handle 17 in a clockwise direction the cam surface 18 is caused to ride up on the bracket 19, thereby forcing the upper end of its hub part 20 against the undersurface of the hub 44 of a wheel 37 and lifting the plug 5 from its seat. The wheel 37 is screwed on the upper end of the stem 14 and is secured thereto by means of the key 38. Turning the handle 90 17 in the reverse direction permits the plug 100

to be seated by the action of gravity and by the spring 13 interposed between the inner end of the bracket 19 and a collar 21 secured to the stem 14.

5 The plug 5 is a hollow structure consisting of a disk-like bottom 22 and a flattened cone-shaped top 23, the sides of the plug being formed by the cylindrical portion 24 and the beveled seating surface 6. The plug 10 5 is guided in its vertical movements within the upper part of the pipe 8, when it is manipulated to open and close the outlet opening, by means of the webs or ribs 25 depending from the undersurface of the bottom 15 22 of the plug. There are four ribs 25 arranged in the form of a cross. This arrangement of the ribs 25 interferes very little with the discharge of the fluid through the outlet pipe 8 and at the same time holds 20 the plug 5 in shape. The center of the cone-shaped top 23 of the plug 5 terminates in an upwardly extending circular flange 26. The lower end of the valve stem or rod 25 14 has a loose or flexible connection with the plug 5 so that in case the stem 14 is deflected or bent by the movement of heavy fluids within the tank or by the springing or the deflection of the tank shell, the plug 5 is not shifted in its seat. In the lower extremity of 30 the valve stem 14 is formed a transverse slot 40 which loosely embraces the rib 41 extending across the upper surface of the bottom 22 of the plug. The lower end of the stem 14 is threaded externally to receive loosely 35 a gland 28 which is also threaded externally to screw loosely into the circular flange 26 of the plug 5. Leakage from the interior of the plug past the gland is prevented by the packing 29 which is forced against the 40 underside of the gland by a nut 30 threaded onto the lower extremity of the stem 14. The gland 28 is prevented from turning by the engagement of a pin 32 (which fits loosely in a hole in an arm extending laterally from 45 the upper end of the gland), with one of the wings 33 projecting radially from the upper surface of the top 23 of the plug and from the exterior of the circular flange 26. By lifting the pin 32 and turning the gland 50 28 in the proper direction a greater or less force may be exerted on the packing 29. This connection between the lower end of the stem 14 and the plug 5, although it is loose or flexible enough to compensate for any 55 deflection of the valve stem, is sufficiently tight to prevent the escape of lubricant upwardly from the chamber 43 past the screw threads.

60 The regrinding of the bearing or seating surfaces 6 and 7 is effected by introducing lubricant containing an abrasive substance, such as emery or carborundum, into the interior or chamber 43 of the plug 5, forcing the grinding mixture out through the radial holes 35 in the beveled seat 6 of the plug and

imparting a rotary motion to the plug while it is held against its seat. The mixture of lubricant and abrasive substance is fed into the chamber 43 of the plug 5 through the hollow valve stem 14. The upper end of the valve stem is threaded internally to receive a screw 36 by turning which the grinding mixture in the plug 5 is forced out through the holes 35. The plug is rotated by means of the wheel or handle 37, the cam member 16 remaining in the position shown in Figs. 1 and 2 while the valve stem 14 rotates.

70 The mode of operation of the improved valve may be briefly recapitulated as follows: The valve is opened and closed in the usual 80 manner by turning the handle 17. By moving the handle 17 in a clockwise direction the cam surface 18 is caused to ride up on the inner end of the bracket 19 and thereby lift the plug 5 from its seat. By turning the handle 17 in a counter-clockwise direction the spring 13 is permitted to force the plug 85 against its seat and thereby seal the outlet opening through the pipe 8. When it is necessary to lap or regrind the bearing or 90 seating surfaces of the valve, the cam member 16 does not turn, that is, ride up on the plate 19 when the wheel-handle 37 is turned. The chamber 43 and the hollow stem 14 having 95 been filled with a grinding mixture consisting of a mixture of lubricant and fine emery, the screw 36 is turned to put the grinding mixture under sufficient pressure to force it out through the holes 35 in the seating surface 6 of the plug. The pressure exerted 100 upon the grinding mixture by the screw 36 is sufficient to lift the plug 5 slightly from its seat, even when the tank is full of liquid, so that as the wheel-handle 37 is rotated the grinding mixture is smeared over the 105 bearing surfaces of the plug and its seat 7 in the upper end of the pipe 8. The wheel-handle 37 is continued to be rotated until the bearing surfaces of the valve are thoroughly lapped or reground and a tight joint 110 thereby produced.

115 Inasmuch as it is one of the features of the present invention to effect a regrinding of the seating surfaces of the valve while the tank car or other structure is in use and contains liquid it is necessary that the lubricant used in the grinding mixture be insoluble in gasoline and the mineral oils. After the seating surfaces of the valve have been reground, the screw 36 will be given an extra turn to force more grinding mixture between the contacting seating surfaces to act as a seal.

120 It will be understood that the valve shown in the drawings and described above is illustrative only, and that the invention is not to be restricted to this specific form of valve, inasmuch as it is applicable to other forms 125 and types of outlet valves for tank cars and similar structures. An important feature 130

of the invention is the provision of means for introducing a grinding mixture between the movable member or valve proper and its seat and then rotating the movable member against its seat to grind the contacting or seating surfaces.

Having thus described the invention, what we claim as new is:—

1. A valve for tank cars and the like comprising, a casing constituting an outlet opening located in the bottom of the tank, said casing having a valve seat, a hollow movable valve member having a bearing surface adapted to be seated against the valve seat in the casing, openings from the bearing surface to the interior of the movable valve member, a hollow valve stem loosely connected with the movable valve member and extending upwardly within the tank, said hollow valve member and the stem being adapted to contain a grinding mixture, means for putting the grinding mixture under pressure to force it out through the openings in the bearing surface, and means for rotating the movable valve member against its seat.
2. A valve for tank cars and the like comprising, a casing serving as an outlet opening located in the bottom of the tank and having a beveled annular valve seat, a hollow plug having an annular bearing surface adapted to seat against the valve seat, openings from the annular bearing surface to the interior of the plug, a hollow valve stem loosely connected with the plug and extending upwardly within the tank, said plug and stem being adapted to contain a grinding mixture, a screw in the top of the stem for forcing grinding mixture through the openings in the bearing surface, and means for rotating the plug against its seat.
3. A valve for tank cars and the like comprising, a casing constituting an outlet opening located in the bottom of the tank and having a valve seat, a movable member having a bearing surface adapted to seat against the valve seat, means for rotating the movable member against its seat from the top of the tank, and means for introducing a grinding mixture between the bearing surface and the valve seat.
4. A valve for tank cars and the like comprising, a casing constituting an outlet opening located in the bottom of the tank and having an annular valve seat, a plug having an annular bearing surface adapted to seat against the annular valve seat, a stem connected with the plug and extending upwardly within the tank, means connected with the stem for rotating the plug against its seat, and means for introducing a grinding mixture between the bearing surface and the valve seat.
5. A valve comprising, a casing having an annular valve seat, a hollow movable member having an annular bearing surface adapted to seat against the annular valve seat, outlet openings between the interior of the movable member and the annular bearing surface thereof, said hollow member being adapted to contain a plastic substance, means for putting the plastic substance under pressure to force it out through the openings and means for manipulating the hollow member.
6. A valve comprising, a casing having an annular valve seat, a hollow plug adapted to be seated against the valve seat and having openings from its interior to its bearing surface, means whereby a plastic substance may be introduced into the plug, means for putting the plastic substance in the plug under pressure to force it out through the openings in its bearing surface, and means for rotating the plug against the valve seat without lifting it therefrom.
